APPARATUS FOR INTRODUCING LIQUID FUEL INTO INTERNAL COMBUSTION ENGINES

Application filed December 21, 1929, Serial No. 415,630, and in Sweden January 2, 1929.

The present invention relates to the introduction of liquid fuel into internal combustion engines and has particular reference to injection nozzles of the type adapted to 5 impart a whirling motion to the fuel before it reaches the discharge orifice or orifices of the nozzle.

Amongst the more important objects of the invention are; to provide an improved 10 nozzle from which one or more fuel jets will issue in a very definite direction or directions, which definite direction or directions will be maintained under all operating conditions; to provide an improved nozzle of 15 very simple construction which is easy to manufacture and in which the possibility of clogging is minimized; and to provide an improved nozzle, the form of which readily permits comparatively wide latitude in the 20 choice of the angle or angles at which the nozzle jet or jets issue, with respect to the longitudinal axis of the nozzle. The manner in which the above objects of the invention 25 are obtained together with other and more specific features of the invention will appear more fully in conjunction with the ensuing description of suitable forms of apparatus for carrying the invention into effect.

In the accompanying drawing forming a 30 part of this specification:

Fig. 1 is a side elevation, partly in section, of one embodiment of the invention;

Fig. 2 is another view of the same embodiment taken at right angles to the plane of 35 Fig. 1;

Fig. 3 is an end view of the inner member of the nozzle shown in Figs. 1 and 2;

Fig. 4 is a view similar to Fig. 1 of another 40 embodiment of the invention;

Fig. 5 is a longitudinal section of the embodiment shown in Fig. 4 and at right angles to the plane of Fig. 4; and,

Fig. 6 is an end view of the inner member 45 of the nozzle shown in Figs. 4 and 5.

Referring to Figs. 1 to 3 of the drawing, the numeral 1 indicates the outer member of the nozzle which is in the form of a cylindrical sleeve open at one end and closed at 50 the other end. The open end is provided with

a base flange 2. The spherically curved inner and outer surfaces of the closed end portion of the sleeve are concentric with respect to each other. Two discharge orifices 4 are formed in the hemispherical end portion 3 of sleeve 1 although it is to be noted that a single orifice or more than two orifices may be used. The centre lines of the orifices 4 intersect in the centre of curvature of the spherical surfaces of the sleeve portion 3. 55 Inserted in the sleeve 1 is a plug 5 exactly or substantially exactly fitting within the sleeve, said plug 5 being formed with a hemispherical end portion corresponding to the inner hemispherical surface of the sleeve portion 3. Formed in the hemispherical end portion of the plug in register with each discharge orifice 4 is a cylindrical recess 6 situated coaxially relatively to the corresponding orifice, the diameter of the recesses being 60 preferably two to four times that of the orifices 4. Leading to each recess 6 is a fuel supplying passage formed by an open groove 7 in the plug 5 and extending longitudinally from the base end of the plug to the respective recess 6 into which the groove opens eccentrically or tangentially. By insertion of the plug into the sleeve said grooves will be closed by the wall of the sleeve so as to form closed passages. Through these passages liquid fuel under high pressure is adapted to 65 be supplied. Such fuel when entering the recesses 6 will be caused to perform an intense whirling motion therein. Said motion will propagate into the discharge orifice, 70 causing an extremely good atomization of the fuel.

In order to secure the maintenance of an exactly definite direction of the injected fuel jets, which is of great importance for many kinds of engines, the length of the discharge orifices 4 should not be too small as compared with the diameter of the orifices. By constructing the injecting nozzle in the manner above described it will be easy to keep said 75 length comparatively great, as for instance, equal to the diameter of the orifices or still greater.

The embodiment shown in Figs. 4-6 differentiates from that above described mainly in 80

that a common fuel supplying passage is provided for two discharge orifices. Said passage comprises a longitudinally extending groove 8 formed in the plug 5, said groove having inclined side surfaces the inclination 5 of which corresponds to the angle which the centre lines of the orifices and recesses 6 form with the axis of the sleeve and plug, as will appear from an inspection of Fig. 4. The inclined side surfaces of the groove 8 will, 10 as a result, cut the recesses 6 along planes which are parallel to the axes of the recesses, and at a comparatively large distance therefrom. This will cause the fuel when entering a recess 6 to perform a rotary motion 15 about the axis of the recess while eliminating the tendency of eddy motions.

From the drawing it will be observed that fuel is introduced into the recesses 6 in a manner such that it is not directed toward 20 the orifices 4 as it leaves the supply channels 7 or 8, but is supplied to the recesses in a direction such that the tendency of the fuel is to rotate generally normal to the axes of the recesses and to move axially of the recesses 25 toward the orifices only because of the pressure under which the fuel is supplied.

It will further be observed that by making the closed end portion of the sleeve 1 with 30 concentric spherically curved surfaces and by having the center lines of the orifices 4 intersect the center of curvature of the spherically curved surfaces, the orifices 4 will take the form of passages, the ends of which are 35 defined by circles lying in planes normal to the axes of the orifices, regardless of the angle at which the axes of the orifices lie with respect to the longitudinal axis of the nozzle. Thus it is possible to form the nozzle with 40 one or more orifices for directing fuel at any desired angle with respect to the longitudinal axis without having to alter the general form of construction of the nozzle, and regardless of the angle of any given orifice, the character 45 of the orifice channel remains in a form such as to definitely project the fuel in a jet which is symmetrical about the axis of the orifice. It is to be noted that the embodiments 50 above described are examples only and that modifications may be made without departing from the principle of the invention.

What I claim is:

1. A nozzle for injecting liquid fuel into internal combustion engines comprising a 55 sleeve having a hemispherical end portion and one or more discharge orifices angularly disposed with respect to the axis of the sleeve in said end portion and a plug fitted in said sleeve, said plug having a corresponding 60 hemispherical end portion and the end portion of the plug having one or more cylindrical recesses, each recess being in coaxial communication with an orifice, and said plug having a fuel supply channel communicating 65 substantially tangentially with each recess.

2. A nozzle for injecting liquid fuel into internal combustion engines comprising a sleeve having a hemispherical end portion and one or more discharge orifices in said end portion, each orifice having an axis disposed at an angle to the axis of the sleeve, and a plug fitted in said sleeve, said plug having a corresponding hemispherical end portion, and the end portion of the plug having one or more cylindrical recesses, each recess having a larger diameter than the diameter of the orifice with which it communicates and said plug having a fuel supply channel communicating substantially tangentially with each recess. 70 75

3. A nozzle for injecting liquid fuel into internal combustion engines comprising a sleeve having a hemispherical end portion and a plurality of discharge orifices in said end portion, each orifice having an axis disposed at an angle to the axis of said sleeve, and a plug fitted in said sleeve, said plug having a corresponding hemispherical end portion, and the end portion of the plug having one or more cylindrical recesses, each recess having a larger diameter than the diameter of the orifice with which it communicates and said plug having a fuel supplying groove formed therein, said groove having inclined side surfaces and communicating substantially tangentially with each recess. 80 85 90 95

4. A nozzle for injecting liquid fuel into internal combustion engines comprising a sleeve having a hemispherical end portion and a plurality of discharge orifices in said end portion, each orifice having an axis disposed at an angle to the axis of said sleeve and a plug fitted in said sleeve, said plug having a corresponding hemispherical end portion and the end portion of the plug having one or more cylindrical recesses, each recess having a larger diameter than the diameter of the orifice with which it communicates, said plug having a fuel supplying groove formed therein, said groove having inclined side surfaces and communicating substantially tangentially with each recess, and the angle of inclination of said side surfaces being equal to the angle formed between the axis of the sleeve and the axis of each orifice. 100 105 110 115

5. A nozzle for injecting liquid fuel into internal combustion engines comprising a sleeve having a hemispherical end portion and an orifice in said end portion, the axis of said orifice being at an angle to the axis of the sleeve, a plug having a hemispherical end portion, said plug being adapted to fit closely within said sleeve and having a cylindrical recess in its hemispherical end portion adapted to register coaxially with said orifice and a channel in said plug, said channel opening into said recess substantially tangentially and in a direction with respect to the axis of the recess to cause rotation of the fuel in 115 120 125 130

the recess generally normal to the axis thereof.

6. A nozzle for injecting liquid fuel into internal combustion engines comprising a sleeve having a hemispherical end portion and a plurality of orifices in said end portion, the axis of each of said orifices being at an angle to the axis of the sleeve, a plug having a hemispherical end portion adapted to fit closely within said sleeve, said plug having a plurality of cylindrical recesses situated so that each recess registers coaxially with an orifice, said recesses being of larger diameter than said orifices, and channel means in said plug for supplying fuel in substantially tangential direction to said recesses.

7. A nozzle for injecting liquid fuel into internal combustion engines comprising a sleeve having a hemispherical end portion and a plurality of orifices in said end portion, the axis of each of said orifices being at an angle to the axis of the sleeve, a plug having a hemispherical end portion adapted to fit closely within said sleeve, said plug having a plurality of cylindrical channels situated so that each recess registers coaxially with a separate orifice, and separate channels in said plug, each channel communicating substantially tangentially with a recess and forming with said sleeve a passage for supplying fuel to its communicating recess in substantially tangential direction and in a direction with respect to the axis of the recess to cause rotation of the fuel in the recess generally normal to the axis thereof.

8. A nozzle for injecting liquid fuel into internal combustion engines comprising a sleeve having a hemispherical end portion and a plurality of orifices in said end portion, the axis of each of said orifices being at an angle to the axis of the sleeve, a plug having a hemispherical end portion adapted to fit closely within said sleeve, said plug having a plurality of cylindrical recesses situated so that each recess registers coaxially with a separate orifice, and a single channel in said plug communicating substantially tangentially with each of said recesses, said channel forming with said sleeve a passage for supplying fuel to each recess in substantially tangential direction and in directions with respect to the axes of the respective recesses to cause rotation of the fuel in the recesses in directions generally normal to the axes of the respective recesses.

9. A nozzle for injecting liquid fuel into internal combustion engines comprising a sleeve having a hemispherical end portion and a plurality of orifices in said end portion, the axis of each of said orifices being at an angle to the axis of the sleeve, a plug having a hemispherical end portion adapted to fit closely within said sleeve, said plug having a plurality of recesses of circular cross section situated so that each recess registers

coaxially with a separate orifice, and a single channel in said plug communicating substantially tangentially with each of said recesses, said channel and said sleeve forming a passage communicating with each of said recesses for supplying fuel thereto in substantially tangential direction, said channel having inclined side walls and the angles of inclination of said side walls being substantially equal to the angles formed between the axis of the sleeve and the axes of the recesses.

10. A nozzle for injecting liquid fuel into internal combustion engines comprising an outer member having a wall portion with concentric spherically curved inner and outer surfaces, an inner spherically curved member adapted to seat against said inner surface, said outer member having a discharge orifice of circular cross-section extending through said wall portion radially with respect to the center of curvature of said inner and outer surfaces, said inner member having a recess of circular cross-section of larger diameter than said orifice in coaxial communication with said orifice and said inner member having a channel in communication with said recess for supplying fuel thereto in substantially tangential direction.

11. A nozzle for injecting liquid fuel into internal combustion engines comprising a sleeve having an end portion having concentric spherically curved inner and outer surfaces and a plug fitted in said sleeve, said plug having a spherically curved end portion seating against said inner surface, the end portion of said sleeve having a cylindrical discharge orifice extending therethrough radially with respect to the center of curvature of said surfaces and angularly with respect to the axis of the sleeve, said plug having a recess of circular cross-section and of larger diameter than said orifice in coaxial communication with said orifice and said plug having a channel communicating with said recess for supplying fuel thereto in substantially tangential direction.

12. A nozzle for injecting liquid fuel into internal combustion engines comprising a sleeve having a hemispherical end portion having concentric inner and outer surfaces and a plug fitted in said sleeve, said plug having a hemispherical end portion seating against said inner surface, the end portion of said sleeve having a cylindrical discharge orifice extending therethrough radially with respect to the center of curvature of said surfaces and angularly with respect to the axis of said sleeve, said plug having a cylindrical recess of larger diameter than said orifice in coaxial communication with said orifice and said plug having a channel in communication with said recess for supplying fuel thereto in substantially tangential direction, said channel having an inclined side wall and the angle of inclination of said side wall being substan-

tially equal to the angle formed between the axis of the sleeve and the axis of said recess.

13. A nozzle for injecting liquid fuel into internal combustion engines comprising a sleeve having a hemispherical end portion having concentric inner and outer surfaces and a plug fitted in said sleeve, said plug having a hemispherical end portion seating against said inner surface, the end portion of said sleeve having a plurality of cylindrical discharge orifices extending therethrough radially with respect to the center of curvature of said surfaces and angularly with respect to the axis of said sleeve, said plug having a plurality of cylindrical recesses of larger diameter than said orifices, each recess being in coaxial communication with an orifice and said plug having a channel in communication with a plurality of recesses for supplying fuel thereto in substantially tangential direction, said channel having inclined side walls and the angles of inclination of said side walls being substantially equal to the angles formed between the axis of the sleeve and the axes of the recesses with which said channel communicates.

In testimony whereof I have signed my name.
